COMBINED AMPLIFIER AND LOUDSPEAKER FOR ELECTRICAL MUSICAL INSTRUMENTS

Thomas A. Walker, Tustin, Calif., assignor to
Music Man, Inc., Anaheim, Calif.

Filed Oct. 5, 1973, Ser. No. 404,106

Term of patent 14 years

Int. Cl. D14—01, 03

U.S. Cl. D26—14 G

FIG.—1

FIG. — 2

FIG. — 3

FIG. - 4

FIG. - 5

FIG. 1 is a perspective view of a combined amplifier and loudspeaker for electrical musical instruments showing my new design;

FIG. 2 is a top plan view thereof;

FIG. 3 is a front elevation view thereof;

FIG. 4 is a rear elevation view thereof; and

FIG. 5 is a right side elevation view thereof.

I claim:

The ornamental design for a combined amplifier and loudspeaker for electrical musical instruments, substantially as shown and described.
